ABSTRACT

Selected compounds having an amidoxy group are useful in preserving cut flowers.

4 Claims, No Drawings

**1
SELECTED AMIDOXY COMPOUNDS AS FLOWER
PRESERVATIVES**

BACKGROUND OF THE INVENTION

1. Field of the Invention

This invention relates to the extension of shelf life of flowers by the use of small amounts of amidoxy-containing compounds preferably in the presence of a sugar or an energy source.

2. Prior Art

Considerable effort has been made to extend the life of cut flowers. Flower preservatives that have been suggested include energy sources (soluble polyhydroxy compounds such as sugars), acids, bactericides, fungicides, metal ions, antioxidants, surfactants, plant hormones such as the gibberellins, etc. Although some of these do extend the life of cut flowers, there is room for additional improvement.

DESCRIPTION OF THE INVENTION

We have now found that compounds of the following structures are effective in extending the life of cut flowers:

and

wherein

X = alkyl or hydrocarbyl of up to 12 carbons or NHR with R being H, hydrocarbyl or chlorohydrocarbyl of up to 12 carbons;

R^1 = H or alkyl of up to 12 carbons;

R^2 = H, alkyl of up to 12 carbons, ammonium, alkali metal or alkaline earth metal ion;

R^3 = H or alkyl of up to 5 carbons; and

R^4 = H, alkyl or amino-containing hydrocarbyl of up to 5 carbons;

These compounds are employed in aqueous solutions at a concentration of at least 1 ppm and generally less than 1000 ppm based on the weight of the solution. For maximum flower preservation, the solution is at a pH of 4-5 and contains a mono- or di-saccharide such as sucrose, glucose, mannose, fructose, etc.

Included within the scope of this invention are amidoxy compounds of the following types:

a. The α -ureidoxy carboxylic acids and their derivatives that are useful in flower preservation have the formula

wherein R is H, hydrocarbyl or chlorohydrocarbyl of up to 12 carbons; R^1 is H or alkyl of up to 12 carbons; and R^2 is H, alkyl of up to 12 carbons, and ammonium, alkali metal and alkaline earth metal salts. These compounds are described in U.S. Pat. No. 3,282,987.

Particularly useful and preferred for flower preservation are those of the above general formula wherein the R groups are hydrogen or 1-3 carbon alkyl groups.

b. The oxadiazinediones, or their corresponding tautomers, have the formulas

wherein R^3 is H or alkyl of up to 5 carbons and R^4 is H, alkyl of up to 5 carbons or amino-containing hydrocarbyl of up to 5 carbons. These compounds are described in U.S. Pat. No. 3,238,200. It is noted these latter compounds have been prepared from α -ureidoxy compounds as described above by treatment with an alkali metal lower alkoxide. The α -ureidoxy carboxy compounds in turn can be obtained from an α -amidoxy carboxylic compound of the formula

wherein R is H, hydrocarbyl or chlorohydrocarbyl of up to 12 carbons which are also useful as flower preservatives. These compounds are obtained by reaction of

the previously shown α -amidoxy carboxylic compound ($\text{H}_2\text{NOCR}^1\text{HCOOR}^2$) with hydrocarbyl acid chlorides of 1-13 carbons including formyl, acetyl, propionyl, decanoyl, benzoyl, and p-chlorobenzoyl.

Preferably in the above compounds, the R , R^1 , R^2 , R^3 and R^4 groups are H or alkyl of up to 4 carbon atoms.

Extended flower preservation is facilitated by the addition of a sugar (i.e., mono- or di-saccharide), such as sucrose, in amounts of 1-5% by weight based on the water solution.

SPECIFIC EMBODIMENTS OF THE INVENTION

The following examples, in which the amounts and conditions are specified, are non-limitative examples of the invention.

Example 1

"Ohio White Sin" carnations of 45 cm in length were harvested at the tight bud stage. Five cm of the basal stem was removed and the fresh weight determined. Flower buds were dipped for 5 seconds in various solutions and two carnations were placed in 250 ml of each test solution in a graduated cylinder. Fresh weight and

solution uptake were determined daily. With water as the control, a vase life of about 9 days resulted whereas with the methyl ester of 2-ureidoxypropionic acid at 100 and 500 ppm, a vase life of 15 and 16 days resulted.

When the above procedure was repeated except that 1000 ppm of methyl 2-ureidoxypropionate was used, a vase life of about 17 days resulted. Addition of 3% sucrose to corresponding control and solutions containing 500 and 1000 ppm of the ureido compound gave vase life time of 11 days (sucrose alone), 18 days (500 ppm of the ureido compound + sucrose) and 19 days (for 1000 ppm of the ureido compound + sucrose).

Example 2

"Ohio White Sin" carnations were harvested at the tight bud stage and the stems cut to provide a length of 30 cm. The basal leaves were stripped and the flowers maintained overnight at 40°F, then placed in sterilized 32 oz glass bottles each containing 250 ml of solution. The flowers were kept under constant incandescent light (50 ft. candles) at room temperature of 70°-72°F with humidity at 40-42%.

The following table shows the vase life of the flowers with various adjuvants.

Adjuvant (by weight)	Vase Life (days)
None (water control)	
3% Sucrose	7
	10
100 ppm in 3% sucrose	20
"	
500 " " " "	17
100 ppm in 3% sucrose	18
"	
500 " " " "	18
100 ppm in 3% sucrose	12
"	
500 " " " "	15

The compounds as defined in this invention are also useful for the preservation of other flowers, e.g., with roses the amount of adjuvant is generally much less than with carnations. Useful amounts are generally 1 to 100 ppm with roses.

55

The embodiments of the invention in which an exclusive property or privilege is claimed are defined as follows:

- 5 1. A method of extending the life of a cut flower which comprises putting the cut stem end of a flower in an aqueous solution containing a compound of the formula

15 wherein

$\text{X} = \text{NHR}$ in which R is H , alkyl or chloroalkyl of up to 3 carbons;

$\text{R}^1 = \text{H}$ or alkyl of up to 3 carbons;

$\text{R}^2 = \text{H}$, alkyl of up to 3 carbons, ammonium, alkali metal or alkaline earth metal ion; the said compound being present to the extent of 100-1000 ppm.

2. The process of claim 1 in which the compound is

3. The method of claim 1 in which the cut flower is a carnation.

4. The method of claim 1 in which the cut flower is a rose.
